DISPENSER

John L. Wilson, St. Paul, Minn.

Application March 11, 1933, Serial No. 660,430

6 Claims. (Cl. 141—9)

The present invention relates to a cleaning material dispenser, and more particularly to a cleaning material dispenser which is particularly adapted for use in dishwashing machines of the spray type.

Various types of cleaning material dispensers have been developed, which are adapted to be positioned in a spray of water in a dishwasher to supply a large charge of cleaning material to the tank of the dishwashing machine when said tank is freshly filled with clear water, and to supply a small charge which continues during the operation of the dishwashing machine to compensate for dilution, which is caused by the fresh rinse water of the machine.

Two of the present general types of dispensers operate either on the principle of having two separate compartments, one for an initial charge of cleaning material, which is subjected to the flow of a comparatively large stream of water diverted from the spray of the dishwasher and adapted to rapidly wash said charge into the tank of the dishwasher, and with a second compartment having a supply of cleaning material therein subjected to the action of a small stream of water, which is also diverted from the dishwasher spray and slowly dissolves the cleaning material therein and adds it to that in the tank of the dishwasher.

A second general type of mechanism for this purpose has a container for cleaning material provided with a slow constant drip mechanism with float control means to maintain a predetermined liquid level in the container to supply a small continuing charge, and having a dump valve for providing a large charge for charging a fresh tank of water in the dishwasher.

The first type of mechanism is open to the objection that the device may be used for but one charging operation, since the cleaning material in the charging compartment is washed completely away and must be refilled for each successive charge.

The second type, while greatly superior to the first, in that it can be used for several successive charges with one filling of cleaning material, nevertheless is somewhat complicated in structure and comparatively expensive to manufacture.

An object of the present invention is to make an improved and simplified cleaning material dispenser.

In order to attain this object, there is provided, in accordance with one feature of the invention, a container adapted to contain a concentrated cleaning solution having a specific gravity greater

than one, said container having a water inlet in the top thereof and a baffle interiorly thereof positioned to deflect a stream of water entering said inlet and dissipate the downward force of said water, and having baffle means enclosing said stream deflecting baffle to dissipate lateral eddy currents from said stream. An overflow opening is provided adjacent said baffle so that when the container is filled to the height of said overflow opening, with a cleaning solution heavier than water, additional water entering said inlet will tend to float on the heavier cleaning solution and to flow out of said overflow opening without mixing with said cleaning solution. By providing a second and smaller inlet to discharge into the interior of the container at a point beyond the confines of said baffle, a small portion of the cleaning solution may be added to the overflow to provide a small continuing charge of cleaning material in the overflow stream. Any desired portions of the concentrated solution may be poured out of the overflow opening by tilting the container at any time desired, the container being preferably of a size to hold sufficient cleaning material for several successive full charges and the smaller, intermediate replenishing charging of the dishwasher in which the device is adapted to be installed.

These and other features of the invention will be more fully brought out in the following description and the accompanying drawing, wherein:

Figure 1 is a view in side elevation of a device embodying the present invention in the act of being tilted to pour out a quantity of concentrated cleaning material therefrom, a portion of a side wall and a side of a baffle enclosure being broken away to show the interior construction.

Figure 2 is a sectional view of the device of Figure 1 taken on the line 2—2 of Figure 3; and

Figure 3 is a plan view of the device shown in Figure 1, all but a corner of the top and screen cover being broken away to show the interior construction.

Referring to the drawing in detail, a container A is preferably constructed of stainless steel, as are all the parts of the present embodiment of the invention, since stainless steel has proved well adapted to withstand the severe corrosive action of the concentrated solutions used, as well as the rough handling to which such devices are frequently subjected.

A baffle enclosure 1 is provided on the inner face of one wall of the container, and within this enclosure the container wall is offset inwardly, as at 2, the upper end 3 of this offset portion being

open to provide an overflow opening. This arrangement of the overflow opening prevents water, flowing down the sides of the container, from finding its way into the interior of the device through the overflow opening. A transverse stream-deflecting baffle 4 is mounted on the wall of the container within the baffle enclosure 1, and is here shown as cup-shaped, but the structure of this baffle is entirely immaterial, providing it performs the function of dissipating the force of a downwardly flowing stream, as will be hereinafter set forth.

A removable cover B has a transverse planiform portion 5 with raised rim 6 and downwardly projecting flange 7, which extends well below the top edge of the container, and preferably is spaced outwardly from the side walls of the container, except at its lower edge to prevent water, flowing down the sides of the container, from working up between the cover flange and the container walls by capillary action, and thence into the container, as has been found to be the result when the cover flange and container side wall are in close proximity throughout.

25 In the cover, and positioned to be directly above the stream-deflecting baffle 4 when the cover is in position on the container A, is a comparatively large opening 8. A second, smaller opening 9 is provided in the cover above a point 30 within the container exteriorly of the enclosure baffle 1. A small pin 10 is loosely mounted in the opening 9 for the dual purpose of loosening any foreign matter which might tend to clog the opening, and to prevent surface tension from holding 35 a drop of liquid on the under side of the opening.

A screen 11 is mounted in a rectangular frame 12, in which is also mounted, below the screen, a perforated plate 13 which supports and reinforces the screen 11. The frame 12 has a downwardly extending flange 14, which engages the cover rim 6 to hold the screen in position thereon.

40 A handle 15 is provided on the exterior of the container wall opposite to that having the overflow opening 3 therein to facilitate tilting the 45 container in pouring out a portion of the liquid contained therein.

Operation

In using the device, the cover B is removed and 50 a quantity of soluble cleaning material, the concentrated solution of which has a specific gravity greater than that of water, is placed in the container, as indicated by the dotted line 16 of Figure 2.

55 The cover is then replaced and the device is positioned in a dishwasher of the spray type, wherein a spray of water is discharged onto the dishes to clean them. The device is positioned in the dishwasher so that a portion of the spray 60 therein will fall onto the cover B, as indicated by arrows 17 in Figure 2, representing the spray. Water is retained in the cover to a depth equal to the height of the rim 6 of the cover, and flows through the openings 8 and 9 into the container 65 A, the excess flowing down the sides of the device. The dispenser is placed in a position within the dishwasher, so that the overflow from the dispenser falls into the dishwasher tank.

70 When the dishwashing machine is operated, the spray of water falling on the cover, rapidly fills the cover up to the edge of its rim 6, and a comparatively large stream of water flows through the opening 8 and fills the container to the overflow level indicated by dotted line 18, 75 Figure 2. The water rapidly dissolves part of the

soluble cleaning material 16 and the water in the tank of the dishwasher may then be "charged" by tilting the container, as shown in Figure 1, to pour a portion of the solution out of the overflow opening, as indicated at 19.

Upon restoring the tank to its normal level position and again operating the dishwashing machine, the container A will again be rapidly filled to the overflow level by water entering the large opening 8. When first starting operation after a 10 fresh supply of soluble cleaning material has been placed in the container, a small amount of solution will flow out of the overflow opening with the water from the opening 8. However, after a few minutes of operation, the heavier 15 cleaning solution sinks in the area confined within the baffle 1, and, the stream-deflecting baffle 4, breaks the downward force of the incoming stream from the opening 8, so the fresh water, or relatively mild cleaning solution 20 sprayed onto the device by the dishwasher sprays, floats on the heavier and more concentrated solution within the container, so that practically 25 none of this solution is carried off with the overflow.

The description of the operation, up to this point, has purposely avoided mention of the function of the smaller opening 9, so as to avoid confusion and to explain clearly the function and operation of the larger opening 8.

Coming now to the small opening 9, this opening permits a relatively small stream or drip of the water or mild solution on the cover to enter the container beyond the confines of the baffle 1. During the filling of the container when dry or partly emptied as after a charging operation, the amount of liquid entering the opening 9 is so small as to be negligible. However, after the machine has been in operation for a few minutes and a more or less balanced condition is attained, then the liquid entering through the opening 9 tends to raise the level of the liquid in the container outside the baffle 1, thus forcing some of the concentrated solution up into the area confined by the baffle 1. The amount of concentrated solution thus added to the overflow is equal, of course, to the amount of liquid entering through the opening 9.

There is thus provided a constant, slow feeding of concentrated cleaning material into the tank 50 of the dishwashing machine, together with means for discharging a large quantity of concentrated cleaning solution from the device for charging a fresh tank of water in the dishwashing machine. The complete absence of floats and valves, 55 or other moving parts, makes this device extremely economical to manufacture, and trouble-free in its operation.

It has been found that even without the use of the smaller inlet orifice 9, that the device will 60 function well enough for all ordinary uses, since upon each stoppage of the dishwasher the flow of water through the large inlet orifice 8 will cease as soon as the liquid level in the top falls to the level of the upper edge of the large opening 65 8. Thereafter the heavier solution in the tank will mix with the water or lighter solution floating on the heavier solution within the baffle 1 and when the dishwasher is again operated a portion of the heavier solution will overflow until 70 a condition of balance is again restored with the lighter liquid floating on the heavier solution. Where comparatively long period of almost continual operation may be encountered, however, 75

it is preferred to use both openings 8 and 9, as illustrated.

I claim:

1. A dispenser for a cleaning solution having a greater specific gravity than water, comprising a tank, a liquid catch basin carried thereby and having a small metering orifice and a second larger orifice opening into said tank, and a vertical baffle interiorly of said tank to enclose a portion of the interior of said tank beneath said second orifice said portion of the tank being in open communication beneath the normal liquid level of said tank, with the interior of said tank beyond the baffle enclosed portion, said tank having an overflow opening within said enclosed portion adapted to discharge exteriorly of said tank, said metering orifice being adapted to introduce liquid into said tank exteriorly of the baffle enclosed portion.
2. In a tank for dissolving soluble cleaning material having a solution of a specific gravity greater than water, a liquid catch basin carried thereby, said catch basin having an orifice opening into said tank, and baffle means mounted beneath said orifice to control eddy currents from a lighter liquid entering said orifice to float such lighter liquid on a heavier solution in said tank, said tank having an overflow opening laterally adjacent said baffle means to permit the overflow of lighter liquid floating on said heavier solution.
3. In a tank for dissolving soluble cleaning material having a solution of a specific gravity greater than water, said tank having an inlet orifice in open communication with a supply of liquid solvent lighter than a solution of said cleaning material, and an overflow opening at a lower level than said orifice, a stream deflecting baffle mounted beneath said inlet orifice and laterally adjacent said overflow opening to control eddy currents from a stream of lighter liquid entering said inlet orifice to float such lighter liquid on a heavier solution in said tank and to divert excess lighter liquid out through said overflow opening.
4. A dispenser for a cleaning solution having a specific gravity greater than water, comprising a

tank, a liquid catch basin carried thereby, a baffle enclosure arranged in said tank, said catch basin having a relatively large orifice opening into said baffle enclosure, and a small metering orifice opening into the tank exteriorly of said baffle enclosure, said tank having a communicating opening with said enclosure, and said enclosure having a large overflow opening arranged to discharge exteriorly of said container, and having a transverse baffle portion laterally adjacent said overflow opening to discharge excess solvent exteriorly of said tank.

5. In a tank for dissolving soluble cleaning material having a solution of a specific gravity greater than water, said tank having an inlet orifice in open communication with a supply of liquid solvent lighter than a solution of said cleaning material, a stream deflecting baffle mounted beneath said inlet orifice and having a laterally extending portion at a point adjacent the normal liquid level in said container, said tank having an overflow orifice materially larger than said inlet orifice at a point laterally adjacent the laterally extending portion of said baffle to control eddy currents from a stream of liquid solvent entering said inlet orifice to float such lighter liquid on a heavier solution in said tank to deflect excess lighter liquid out through said overflow opening.

6. A dispenser for a cleaning solution having a specific gravity greater than water, comprising a tank, a liquid catch basin carried thereby, an enclosure in said tank, said catch basin having a relatively large inlet orifice opening into said enclosure, and having a small metering orifice opening into said tank exteriorly of said enclosure, the main portion of said tank having a communicating opening with said enclosure and being adapted to receive a soluble cleaning substance, the solution of which is of greater specific gravity than the solvent to be employed, said tank having a large overflow opening within said enclosure, and baffle means mounted laterally adjacent said overflow opening to deflect excess solvent therethrough.
